KNITTING MACHINE

Louis H. Mendelsohn, Paterson, N. J.

Application March 2, 1942, Serial No. 433,048

5 Claims. (Cl. 66—89)

My invention relates to straight knitting machines and it is an object of the same to provide improved means in connection with the covering motion of such a machine whereby the diamond points of a full-fashioned stocking can be outlined by a series of openings or lace stitches so as to provide a novel and pleasing appearance at this part of the stocking. For this purpose transfer points are omitted at appropriate places in the wide and narrow combs and the shape of the covering knife is altered, all as hereinafter more fully set forth. Only so much of the machine is shown in the accompanying drawing as is necessary to a disclosure of my invention, but the machine may be of the well-known type made by the Textile Machine Works of Reading, Pa., or of any of the other types known in the art. For a fuller disclosure of conventional parts and mechanisms reference may be had to Pat. No. 2,101,048, December 7, 1937, to A. E. Ischinger.

Referring to the drawing, which is made a part of this application and in which similar reference characters indicate similar parts,

Fig. 1 is a front elevation of so much of a straight knitting machine as will suffice to illustrate my invention.

Fig. 2, a fragmentary knitting diagram, and

Fig. 3, an elevation of the foot portion of a stocking embodying features that may be made by the use of my invention.

In the drawing, reference character 10 indicates a series of needles as used in a straight knitting machine, said machine having wide transfer combs 11, 12, carried respectively by rods 13, 14, and narrow transfer combs 15, 16, carried respectively by rods 17, 18, the wide and narrow combs at each side of a section being shown as separated by the space of one needle, as usual, between narrowing operations or dips of the narrowing devices, when knitting the toe of a stocking. Two transfer points next to the innermost one (hereinafter referred to as the first point) on each of the narrow combs are removed or omitted from the comb, and in each of the wide combs the third point, counting from the inner end of the row of points thereon, is also removed or omitted. It will be understood that only about one-fourth of the usual number of points is shown in each comb, as a matter of convenience.

The covering knife is shown at 19, it being mounted as usual on an oscillatory rod 20 for swinging into and out of the operative position where it covers the needles and prevents the points from taking off their loops. Although proportions are not essential the covering knife

is here intended to be shown as being widened laterally at each side by a distance equal to the single needle space of the gap at 21 plus the width of the projection beyond the gap, the width of the projection being equal to two needle spaces.

The operation of the transfer points in knitting the toe is the conventional one for making a diamond point at each side of the toe except as hereinafter explained, the points dipping to remove loops from corresponding needles, the wide combs then moving inward two needle spaces after being lifted and pushing the narrow combs inward one needle space before all are dipped again to replace the loops on other needles of the series, so that each loop taken off by a wide comb is moved inward two needle spaces and each one taken off by a narrow comb is moved inward one needle space, except as hereinafter described.

20 During the knitting of the parallel-sided portion of the diamond point each transfer point 22 in a wide comb at one side of the stocking will pick up a stitch at each dip and transfer it to a needle of the series 10 two needle spaces inward as usual, the comb moving two spaces inward and later one space back as usual, and thus a loop will be placed on each of the needles 23, 24, as indicated by vertical lines in the diagram of Fig. 2. But since the loop originally on needle 23 was not removed, due to the absence of a point at the third position in comb 11 or 12, there will be two loops on that needle as indicated by the cross at 23' in Fig. 2, wherein straight vertical lines indicate single loops or stitches, crosses indicate double loops or stitches, and O's indicate a hole caused by absence of a loop, due to the fact that the loop of that needle has been transferred to another needle and has not been replaced by another loop. Only the courses wherein transferring occurs are indicated, the blank row between rows of indications corresponding to an interposed course of plain knitting.

Successive operations such as described will result in a slight ridge along the line of such doubled loops, which ridge will be parallel to the wales in the diamond point but oblique to the selvage adjacent to said ridge. Since the loop on needle 23 was not transferred to needle 25 a hole will be formed at 25' and thus a line of holes adjacent the ridge formed by the doubled loops, this row of openings being along the outer margin of the diamond point, as shown at 27 in Fig. 3. Also, since the original loop was not removed from needle 26 there will be formed at each transfer operation a doubled loop at that needle, indi-

cated at 26' in Fig. 2, and so another ridge along the inner side of the row of holes.

In the case of the narrow comb the first point 28 is retained while the second and third points are removed or omitted. Since this comb moves over only one space, during this part of the operation, for each dip there will be a double loop on needle 29, a single loop on needle 30, because its loop was not taken off the needle, no loop on needle 31 whose loop was taken by point 28, and a double loop on needle 32 after a transferring operation, all as indicated diagrammatically at 29', 30', 31' and 32' in Fig. 2, and thus a line of lace openings paralleled by ridges will be formed also along the instep side of the diamond point at 37 in Fig. 3 in the successive operations of the machine at this part of the toe.

Upon reaching the end of the parallel-sided portion of the diamond point, i. e., at the next dip after that illustrated in Fig. 1, the covering knife is brought down to its operative position where it will be interposed between an increasing number of the needles and the inwardly moving points on the narrow comb, thus preventing removal of loops by the points, all as usual in knitting the diamond point, except as indicated. At this time the "two-step forward and one-step back" movement of the wide comb ceases and that comb moves only forward over a two needle space at each operation and not backward any more. The narrow comb is still being pushed inward one step by the wide comb as the latter moves inward, but is advanced another step after each transfer operation, by some such means as that disclosed in the Ischinger patent above referred to, hence it will still be separated by one needle space from the wide comb between dips, as before.

Assuming that the parts have reached the position above suggested, and that the cover knife has been lowered, it will be seen that on the next following dip (the second row in Fig. 2, counting upward) the point 28 will remove a loop from needle 32 and place it on needle 33, the failure of this needle to receive another loop causing a hole to be formed here, as before the next point in the narrow comb taking a loop from needle 29 and adding it to the loop on needle 30. The wide comb continues as before except that the holes made along the oblique line at 40 in Fig. 3 are each advanced two spaces instead of one, due to the absence of a return movement of this comb at this time.

At the second following dip (row 3 from below in Fig. 2) for removal of stitches the point 28 of the narrow comb is at needle 34 behind the projection at the lower corner of the cover knife 19 and so cannot take off a loop as indicated in the third line (counting upward) of the diagram of Fig. 2. Hence there is no hole formed at the angle 38 between lines 37 and 41 of the diamond point, but the point being advanced two spaces in the manner referred to, it will now be at needle 36, beyond the gap 21, and again cannot take a loop from the needle 36 because of the cover plate, though the next following point transfers a loop from needle 31 to needle 33.

At the third following dip (fourth row from below, Fig. 2) no loops are transferred by the narrow comb, point 28 being at needle 36, as above stated, and moving on to a needle still farther behind plate 19, while the next following point moves from needle 33 to needle 35.

At the next dip (fifth row, Fig. 2, counting from below) the point next after 28 on the narrow

comb takes a loop from needle 35 and transfers it to needle 36, but the points at the fifth and sixth positions on the narrow comb, which are the third and fourth actually present, being now covered by the plate 19, no loop is transferred to needle 35 and therefore a hole occurs at that point in this course.

Similarly at each dip thereafter up to the point 39 in Fig. 3 there will be a hole at needle 35, and such holes will all be in the same wale, or parallel to the adjacent selvage. The above-described action is of course identical at both sets of combs, thus producing similar diamond points at each side of the stocking toe in the manufacture of fashioned hosiery.

Thus by means of my invention I am able for the first time to make a diamond point completely outlined by openings for ornament and ventilation, said openings being made by transferred stitches.

It will be obvious to those skilled in the art that changes may be made in the mechanism shown in the drawing and described in the specification, all without departing from the spirit of the invention; and therefore I do not limit myself to what is so shown and described, but only as indicated in the appended claims.

Having thus fully described my said invention, what I claim is:

- 30 1. In a full-fashioned knitting machine, narrowing mechanism comprising a covering knife having gaps in its lower edge adjacent each side of the knife, a narrow comb at each side of the knife, and a wide comb beyond each narrow comb, each narrow comb having a series of points interrupted at the second and third places from the inner end of the series, and each wide comb having a series of points interrupted at the third place from the inner end of the series.
- 35 2. In a full-fashioned knitting machine, narrowing mechanism comprising a covering knife having gaps in its lower edge adjacent each side of the knife, a narrow comb at each side of the knife, the combs each having a series of points interrupted at a place spaced inwardly from the inner end of the series, and a wide comb beyond each narrow comb.
- 40 3. In a full-fashioned knitting machine, narrowing mechanism comprising a covering knife having gaps in its lower edge adjacent each side of the knife, and a comb at each side of the knife, each comb having a series of points interrupted equidistantly from the inner end of the series.
- 45 4. In a full-fashioned knitting machine, a series of needles, narrowing mechanism comprising a covering knife, a wide comb at each side of said knife, a narrow comb between said knife and each of said wide combs, each of said combs having a series of points spaced correspondingly to said needles, and there being vacancies in each series adjacent but spaced from the inner end of the series.
- 50 5. In a full-fashioned knitting machine, a series of needles, narrowing mechanism comprising a wide comb adjacent each end of said series, and narrow combs interposed between said wide combs one adjacent each wide comb each of said wide and narrow combs having a series of points spaced correspondingly to said needles and each comb having one or more points omitted adjacent but spaced from the inner end of the series of points thereon.

LOUIS H. MENDELSOHN.
